ELECTRICAL CONTACT MEANS IN WIRE SPRINGS

Harald Valdemar Alexandersson, Lidingo, Sweden, assignor to Telefomaktiebolaget L M Ericsson, Stockholm, Sweden, a corporation of Sweden

Filed Jan. 25, 1961, Ser. No. 84,909

Claims priority, application Sweden Feb. 10, 1960

6 Claims. (Cl. 200—166)

There exists a number of constructions of electrical contact means for relays and selectors used in telephone art, at which wire springs are used instead of the usual leaf springs. The constructions will thereby take less room. In certain cases one makes use of the property of the wire spring of being able to bend a little sideways, perpendicularly to the normal working direction, in order to obtain twin contact effect by means of only one pair of wire springs. The one contact spring then has to be provided with an angle contact, the other contact spring making contact with both angle legs. Such a contact means is generally called V-contact. It is however comparatively difficult to manufacture such a V-contact and it is almost impossible to apply a suitable contact material on the contact points in another way than galvanically, which gives bad contact qualities.

The purpose of this invention is to obtain in a simple way reliable V-contacts on wire springs. This is achieved in such a way that the one contact wire of a contact spring pair is provided with a tube consisting of contact material which tube is fixed on the contact wire in such a way that one portion of the tube is placed outside the free end of the wire and that this portion along the side facing the other contact wire has been given in cross section a V-shape suited for contact giving.

The invention will be further described with reference to the attached drawing. FIGS. 1 and 2 show a perspective view and an end view of a known design of a V-contact means. FIGS. 3 and 4 show in corresponding views the contact means proposed according to the invention.

At the perspective view, shown in FIG. 1, of a pair of wire contact springs fastened at their back ends in the usual manner, the V-contact is formed by the lower contact wire. This is in its fore end, as also appears from FIG. 2, in which a front view of the fore ends of the springs is shown, bent perpendicularly to the wire direction, and shaped as a little hook, in which the upper spring can make contact when the lower spring is brought upwards. The upper spring can thereby be bent a little downwards against the V-contact as is shown in FIG. 1.

At the now proposed construction according to FIGS. 3 and 4, the upper contact spring 1 is in front provided with a cylindrical tube 2 of contact material. The lower spring 3 is a little shorter than the spring 1. A piece of tube 4 is fastened on the fore end of the spring, for example by pressure or by welding. Part of the tube 4 is thereby placed outside the free end of the wire. The tube is so long that the lower contact spring 3 and the projecting portion of the tube 4 together are equally long as the upper contact spring. The projecting portion of the tube 4 is, for example by stamping, so shaped that the upper side adjoining the upper contact wire forms a piece 5 that is V-shaped in cross section, which piece serves as contact point. When the lower spring 3 is lifted by an operating member 6, the cylindrical, upper contact tube 4 will slide into the V-shaped groove 5 and makes contact

2

against its both sides which form an angle with each other. Suitably the V-shaped portion 5 is bent up against the upper contact wire as is shown in FIG. 3, whereby the latter can be made straight.

By providing the two contact springs with tube pieces of contact material it is achieved that a sufficiently large quantity of such material is provided for the use intended for the springs. The geometrical dimensions of the springs will furthermore be such that the contact means in its entirety, from the technical, manufacturing point of view, is easy to make.

I claim:

1. A contact device for switching means, said device comprising a first and a second springy wire, support means supporting said wires in positions in reference to each other in which said wires are movable into engagement, and a sleeve made of contact material fitted upon an end of one of said wires lengthwise protruding therefrom, said protruding sleeve portion having a V-shaped configuration, the open side of the V-shaped portion facing the other wire for receiving said other wire in contact engagement at both inner surfaces of the V-shaped portion.

2. A contact device according to claim 1 wherein a cylindrical sleeve made of contact material is fitted upon one end of said other wire, said sleeve being engageable with the inner surfaces of said V-shaped sleeve portion.

3. A contact device according to claim 2 wherein said V-shaped sleeve portion is bent toward said other contact wire in reference to the axis of the wire on which said sleeve having the V-shaped portion is fitted.

4. An electric switching device comprising a first and a second springy contact wire, mounting means supporting said wires parallel to each other in spaced-apart relationship, switch actuating means engaging one of said wires to flex one end thereof into contact engagement with the adjacent end of the other wire, a sleeve made of contact material fitted upon an end of one of said wires protruding from said end, said protruding sleeve portion having a V-shaped configuration, and a cylindrical sleeve made of contact material fitted upon the adjacent end of the other wire, the open side of the V-shaped sleeve portion facing the sleeve on the other wire for receiving said latter sleeve in contact engagement at both inner surfaces at said V shape.

5. A switching device according to claim 4 wherein said V-shaped portion is bent toward said other sleeve in reference to the axis of the wire mounting said sleeve-shaped portion.

6. A switching device according to claim 4 wherein the wire mounting the sleeve-shaped portion is shorter than the other wire, said protruding V-shaped sleeve portion complementing the shorter wire substantially to the length of the other wire.
